FIG. 7a

AMOS R. HEATH INVENTOR.

BY

Amos Heath Atty

fastened to the clothes pole 6 by screws 9, 9. On the top and bottom the block is grooved transversely as indicated at 10 and 11.

The block is engaged with the clothes line, not when it is in its upright position as is shown in full lines in Figures 1, 2 and 3 but when the clothes pole is in the dotted line position shown in Figure 1. Thereafter the clothes pole is brought to the upright position shown in full lines in Figure 1 and in this way the block not only grips the line but shortens the line as well and the line is raised to the full length of the clothes pole.

In Figure 3 I have shown a modified form of the block in which the block 12 is fastened on the pole 6 by two screws 13, 13. The block 12 in this case is made preferably of sheet metal and has one jaw 14 extending upwardly therefrom and another jaw 15 extending downwardly therefrom, these jaws being shown in side elevation in Figure 3a.

In Figure 4 I have shown the pole 6 having a block thereon which block consists of a flat metal plate 16. This plate and the pole are perforated to receive a binding post 17 and the plate and pole are slotted at 18 to receive a binding post 19 which binding post is movable up and down in the slot 18. These binding posts are fastened at the back by nuts 20, 20. The post 19 can be placed close to the post 17 as shown by dotted lines at 19a or can be placed remote from the post 18 as shown in full lines at 19 in Figure 4.

With the binding posts placed close together as shown in Figure 4 and the clothes pole placed in its dotted line position as above described the line is slack. The clothes pole is then moved from its dotted line to its full position in Figure 1 to grip the line and take up a little slack therein.

With the posts 17 and 19 placed remote from each other the clothes pole can engage with the line as shown in dotted lines in Figure 1 and can then be brought to the full line position shown in Figure 1 in which case it will take up more slack in the line.

As shown in Figure 5, the clothes pole has a block thereon which is in the form of a plate 24 fastened to the clothes pole by two screws 25 and 26. In this block two jaws are formed, namely 27 and 28. One of these jaws opens horizontally to the right and the other jaw opens horizontally to the left.

These jaws are engaged with the line when the pole is in dotted line position as shown in Figure 1 and they grip and tighten the line when the clothes pole 6 is moved to full line position in Figure 1.

In Figures 6 and 6a I have shown the block 1 shown in Figure 2 together with a supplemental block 7a. Both of these blocks are fastened to the pole by screws as described above and both of them have slots 8 and 8a similar to the slot 8 shown in Figure 2.

The slots 8 and 8a are in line or in tandem with each other and the line 5 can be engaged with one or both slots just as it is desired to take up a small amount or great amount of slack in the line when the pole 6 is placed in the full line position shown in Figure 1.

In Figures 7 and 7a I have shown a metal block 32 having a jaw 33 opening upward therein and jaw 34 and jaw 35 opening downward therein. The clothes line 5 will be engaged with the upper jaw and with the jaw 34 or 35 as may be desired to take up little or more slack in the line 5.

In all these blocks the line will be engaged with the block while the pole 6 is in the dotted line position in Figure 1 and the line will be raised and tightened by moving the pole to the full line position in Figure 1.

I claim:

A clothes pole having a substantially rectangular plate secured to one side thereof adjacent one end thereof; said plate having oppositely directed jaws offset from the plane of the plate, said jaws being located in diagonally opposite corners of the plate, one of said jaws extending in a direction toward the adjacent end of the pole and being formed along one side edge of the plate, and the other jaw being oppositely directed and formed along the other side edge of the plate, said jaws being laterally spaced whereby a clothesline may pass over one jaw, extend for a distance parallel with the longitudinal axis of the pole, and thence pass over the other jaw, said pole being pointed at its other end for projection into the ground whereby said pole may be held at a right angle to the ends of said clothesline extending away from the jaws by insertion into the ground.

AMOS R. HEATH.
